UNITED STATES PATENT OFFICE.

CECIL R. ANDERSON, OF PITTSBURGH, PENNSYLVANIA.

MINE DRILL.

Application filed December 10, 1921. Serial No. 521,374.

The present invention relates broadly to mining tools and implements, and more particularly to mine drills or augers.

It has heretofore been customary in the art to which this invention relates to provide the threaded boxings for the threaded feed bars of the drills or augers with pins, keys or clamps adapted to hold the pivoted sections of the boxings in closed position about the feed bars. Due to the conditions under which apparatus of this character is used, independent holding means of this character is objectionable as the keys, pins and clamps become loose or distorted through use due to the fact that poor lighting conditions frequently result in the miners striking the keys or clamps unevenly, or become lost when detached.

By the present invention, these disadvantages are entirely overcome, and there is provided means which is easily operated for holding the pivotally connected sections of the threaded boxings in closed position about the feed bars. Also, with the present invention, the holding means is rendered effective automatically upon the positioning of the boxings in the supports provided therefor.

The foregoing and other objects of the present invention, together with their attendant advantages, will be apparent as the invention becomes better understood by reference to the accompanying specification and drawings forming a part thereof, it being premised that changes may be made in the details of construction and manner of operation without departing from the spirit of my invention or the scope of my broader claims.

Figure 1 is a perspective view of one form of apparatus embodying the present invention;

Figure 2 is a detail sectional view of a portion of the apparatus illustrated in Figure 1;

Figure 3 is an end elevation of the threaded boxing shown in Figures 1 and 2;

Figure 4 is a detail view, partly broken away, of the boxing shown in Figure 2 in position on the support, the support being shown in section;

Figure 5 is a side elevation of a slightly

modified form of boxing in position as illustrated in Figure 4;

Figure 6 is an end elevation of a still further modified construction;

Figure 7 is a sectional view on the line VII—VII of Figure 6, the boxing being removed;

Figure 8 is a side elevation of a modified form of apparatus embodying the present invention;

Figure 9 is a detail view of the construction illustrated in Figure 8;

Figure 10 is a view, similar to Figure 9, illustrating a slightly modified construction;

Figure 11 is a side elevation of a modified form of chair, and

Figures 12 and 13 are side elevations of boxings embodying modifications of the present invention and adapted to be used with the chair shown in Figure 11.

Referring more particularly to Figures 1 to 4, both inclusive, of the drawings, there is illustrated an apparatus embodying a post comprising side bars 2 having their opposite ends connected by suitable heads 3. Carried by the upper head 3 is an adjustable jack screw 4 adapted to be forced into engagement with the roof of a mine shaft, while carried by the lower head 3 is an adjustable foot 5.

Adjustable vertically on the side bars 2 is a slide 6 adapted to be clamped in adjusted position by a suitable clamping device 7. These features of the invention are well known in the art, and constitute no essential part of the present invention. The slide 6, however, has extending transversely thereof a pin 8, adjacent the opposite ends of which are shoulders or bosses 9. Adapted to be supported by the slide 6 is a threaded boxing comprising pivotally connected sections 10. Each of these sections has projecting therefrom in substantially diametrical relationship to the connection for the sections, bearing members comprising lugs 11. These lugs are spaced at their lower ends to provide a passage 12 for the reception of the pin 8, and have their inner surfaces curved in conformity with the periphery of this pin.

The parts are so constructed that the distance between the outside faces of the lugs 11 corresponds substantially to the distance

95

100

between the oppositely disposed faces of the bosses 9, whereby when the threaded boxing is placed in position on the supporting slide 6, the sections 10 will be held in closed position.

The sections 10 of the boxing are provided with internal threads 13 as is customary in this art to cooperate with the threaded feed bar 14 carrying an operating crank 15 at one end thereof and a drill or auger 16 at the opposite end.

In Figure 5 there is illustrated a slightly modified form of boxing in which each of the sections 10 thereof carries but a single lug 17 having oppositely disposed bearing surfaces 18 for cooperation with the pin 8. These lugs are also so disposed that the distance between the outer faces corresponds substantially to the distance between the adjacent faces of the bosses 9 whereby the bosses serve to hold the boxing in closed position about the feed bar without the provision of extraneous fastening pins, keys or clamps.

In Figures 6 and 7 there is illustrated a modified form of slide 6' having a connecting yoke 19 in place of the pin 8. With this construction each of the portions connected by the yoke 19 is provided with an angularly disposed open topped bearing 20 adapted to readily receive projecting pins 21 formed on the sections 10 of the threaded boxing. With this construction, the distance between the outer ends of the projecting pins 21 substantially corresponds to the distance between the inner faces of the connected portions of the supporting slide, whereby it is necessary only to place the parts in position to effectively hold the boxing in operative relation to the threaded feed bar.

In Figure 8 the present invention is shown applied to mining apparatus of the type which embodies a grip bar 22 in place of a post. These grip bars are usually held in position by a grip wedge 23, and are provided with a series of openings 24 formed therein to receive the tail 25 of a supporting chair 26. These chairs correspond in function to the slides, or equivalent structures used where posts are employed, and the general term "support" as used throughout the specification and claims is intended to include the various modifications of this nature. The chair 26 has its side portions connected by a pin 8' provided with end bosses 9'. The boxing illustrated in Figures 8 and 9 corresponds exactly to the boxing shown in Figures 1 to 4, both inclusive, and the same reference characters have been applied thereto.

In Figure 10 there is illustrated a slightly modified construction in which the chair 26' has the side portions thereof provided with angularly extending open topped bearings

20', as shown in Figures 6 and 7, adapted to cooperate with a boxing of the construction illustrated in said figures.

In Figure 11 the chair 28 is illustrated as having bearing pins 29 projecting inwardly from the side portions thereof. These bearing pins are adapted to cooperate with bearing sockets 30 as shown in Figure 12, corresponding in function to the construction illustrated in Figures 1 to 4, or with bearing sockets 31, as illustrated in Figure 13 and corresponding in function with the construction illustrated in Figure 5.

With all of the constructions illustrated herein there is provided a support adapted to receive a sectional boxing in such manner that when the boxing is inserted in position on the support the sections thereof are held in closed position about a feed bar. This entirely eliminates the necessity of providing a separate means for holding the sections of the boxing in closed position and renders the use and operation of the apparatus much easier. The advantages of the present invention arise by reason of these features.

I claim:

1. In an apparatus of the class described, a boxing support having relatively fixed sides, a feed screw, a separable boxing surrounding the feed screw, formed of substantially similarly shaped members, bearings on the boxing and support for rockably supporting the boxing about an axis extending transversely to the axis of the feed screw, said bearings being arranged to maintain the boxing in a fixed working position about the feed screw, regardless of the working pressure on the screw, substantially as described.

2. In an apparatus of the class described, a boxing support having relatively fixed sides, a feed screw, a separable boxing surrounding the feed screw formed of substantially similarly shaped members, means for rockably supporting the boxing about an axis extending transversely to the axis of the feed screw and for maintaining the boxing about the feed screw, said means comprising a bearing face on the support on opposite sides of the feed screw, and bearing faces on the boxing members engaging the bearing faces on the support, substantially as described.

3. In an apparatus of the class described, a boxing support having side members, means on said side members for supporting a boxing for movement about an axis extending from one side to the other, parallel bearing faces on the sides in planes at right angles to said axis, a boxing formed of two members hinged to each other, and means on each boxing member for engaging the boxing supporting means on the support, each of the means on the boxing having a face engaging one of the bearing faces on

the support to retain the boxing in its closed position.

4. In an apparatus of the class described, a feed screw, a boxing support comprising spaced side members, and a sectional boxing adapted to be carried by said members, each section of the boxing having projections the outermost side and end portions of which are engaged by the boxing support, where-
10 by the sections are held in closed position by said members when carried thereby, substantially as described.

5. A boxing for a mine drill feed screw having two similar members hinged to each other, each member having a bearing lug arranged to engage a bearing on a support to permit the boxing to be rocked about an axis transverse to the axis of the feed screw, and a bearing face on each lug in a plane
20 perpendicular to the axis about which the

boxing is rocked, said faces being spaced at a considerable distance apart and arranged to engage similarly spaced faces on the support for retaining the boxing closed, substantially as described. 25

6. In an apparatus of the character de-
scribed, a feed screw, a boxing comprising relatively movable sections, means on each of said sections adapted to cooperate with a boxing supporting means, and boxing 30 supporting means constructed to engage the outermost side and end portions of said first mentioned means and prevent lateral movement of the sections, whereby the sec-
tions are held in closed position entirely by 35 said boxing supporting means, substantially as described.

In testimony whereof I have hereunto set my hand.

CECIL R. ANDERSON.
